PHYSICIAN'S EXAMINING TABLE

James M. Katzfey and Warren J. Peterson, both of Two Rivers, Wis., assignors to Hamilton Manufacturing Company, Two Rivers, Wis., a corporation of Wisconsin

Filed Oct. 11, 1965, Ser. No. 87,409

Term of patent 7 years

(Cl. D83—1)

FIG. 1 is a perspective view showing the front and the foot end of a table embodying our new design;

FIG. 2 is a perspective view showing the back and the head end of the table;

FIG. 3 is a perspective view similar to FIG. 1 but showing a section of the top of the table in a fully raised position;

FIG. 4 is another perspective view similar to FIGS. 1 and 3 but showing the section of the top in a partially raised position;

FIG. 5 is another perspective view similar to FIGS. 1, 3 and 4 but showing the one section of the top in partially raised position and another section fully raised; and

FIG. 6 is an elevational view of the foot end of the table.

The dominant features of our design reside in the portions shown in full lines in the drawings.

We claim:

The ornamental design for a physician's examining table, substantially as shown and described.
